UNITED STATES PATENT OFFICE.

HARRY H. STYLL, OF SOUTHBRIDGE, MASSACHUSETTS.

LENS.

1,267,821.

Specification of Letters Patent. Patented May 28, 1918.

Application filed December 11, 1916. Serial No. 136,241.

To all whom it may concern:

Be it known that I, HARRY H. STYLL, a citizen of the United States, residing at Southbridge, in the county of Worcester 5 and State of Massachusetts, have invented certain new and useful Improvements in Lenses, of which the following is a specification.

My invention relates to improvements in 10 lenses and has particular reference to an improved construction of lens blank for a bifocal lens, and an improved process or method of construction of the lens to secure the most satisfactory results and minimize 15 difficulties previously experienced in the construction of the same.

One of the leading objects of my present invention is the provision of an improved construction of bifocal lens blank which may 20 be readily produced in commercially marketable form, and which shall be so constructed as to facilitate the manufacture of the blank into a finished lens and minimize losses due to slipping or displacement of the segment 25 portion of non-integral or two-piece bifocals during the manufacturing operation.

A further object of my present invention is the provision of a construction in which the segment may be laterally reinforced to 30 prevent any tendency of same to slip at the edges during the grinding or finishing operation.

Other objects and advantages of my improved construction and process of producing bifocal lenses should be readily apparent 35 by reference to the following specification taken in connection with the accompanying drawings, and it will be understood that I may make any modifications in the specific 40 details of construction shown and described within the scope of the appended claims without departing from or exceeding the spirit of my invention.

Figure I represents a plan view of a blank 45 embodying one form of my improvement.

Fig. II represents a similar view of a modified construction.

Fig. III represents a sectional view taken on the line III—III of Fig. I.

Fig. IV represents a similar view taken 50 on the line IV—IV of Fig. II.

Fig. V represents a sectional view illustrating another modified construction.

Fig. VI represents a sectional view of 55 another modification.

Fig. VII represents a plan view of a

lens cut from the style of blank illustrated in Fig. I, the blank from which the lens is cut being shown in dotted line.

Fig. VIII represents a view of a slightly 60 modified construction of finished lens embodying my improvement.

In the drawings, in which similar characters of reference are employed to denote corresponding parts throughout the several 65 views, the numeral 1 designates the major portion of the blank having formed therein the countersink 2 adapted to receive the segment 3, which has the curved lower face adapted to fit the counter sink and a slight 70 surrounding wall 4, the portion inclosed by the wall 4 in practice having to be ground away in the production of the finished lens, as indicated by the dotted lines in Fig. V.

The construction just described has hitherto 75 been employed in the art in connection with the construction of fused bifocal lenses or lenses in which the parts are brought to a temperature sufficient to cause them to melt and flow together, becoming a single 80 integral or homogeneous construction but has not hitherto been employed in connection with what may be termed the cement type of lens, that is to say the type of lens in which the parts 1 and 3 are separate from 85 each other and are united by means of a cement or other adhesive medium so that they remain distinct and may be separated one from the other if desired.

In the case of lenses in which the parts 90 are fused together it has been possible to satisfactorily grind the two-part blank, since on account of their uniting by fusion there is no possibility of relative shifting movement of the segment and major blank, 95 but so far as I am aware prior to my invention no one has conceived the possibility of so securing the segment within the recess that it would be possible to similarly grind a bifocal in which the parts were not integral. 100

I have discovered, however, that by the use of my improvement it is possible to satisfactorily produce lenses of this character. One of the essential features of my 105 invention, therefore, consists in so securing or connecting the parts that there will be some means in addition to the connecting cement for preventing lateral slipping or relative shifting movement of the blank and segment during the grinding operation.

In Figs. I and III, I have illustrated one

form of construction for attaining this result, in which I have shown as drilled through coinciding portions of the segment and major blank, the apertures or sockets 5, adapted to receive a suitable hardened plug or locking member 6, which may be in the form of a cement, amalgam or other substance, which will key or connect the two parts together and prevent relative lateral movement during the twisting or compound rubbing movements which are given to the lens while the surface is being ground thereon.

In Figs. II and IV, I have illustrated another form of my invention in which the segment is disposed with a portion overhanging the edge of the lens and has the lateral recesses 7 formed therein to provide the central dove-tail 8, a suitable cementitious locking medium or the like 9 being secured to the edge of the main blank 1 and having portions projecting and fitting up into the recesses 7 and interlocking with the dove-tail 8 to mechanically retain the dove-tail.

Indicated in Figs. II and IV in dotted lines, as capable of use in conjunction with the structure there illustrated, if desired, and specifically illustrated in the sectional view Fig. VI, is a further possible modification of my invention in which the tapered annulus 10 is employed encircling the projecting portion of the segment and engaging the major blank 1 so that the lateral edges of the segment will be braced during the entire grinding operation, the bracing member 10 being gradually worn away with the segment. This form possesses additional advantages, in that the glass of the segment is laterally braced and any tendency of the segment to chip off during the grinding is thus prevented and an extremely satisfactory invisible line of joinder between the major blank and segment thus assured.

Fig. V represents another form of the invention, in which this same result is similarly obtained. In Fig. V, however, in place of employing the additional bracing device 10, I form the countersink in the blank 1 with a slight surrounding wall 11, a superfluous quantity of cement being placed in the countersink as the segment is applied thereto to fill in any existing space between the edge of the segment and the wall of the countersink. In this way the entire glass is ground away simultaneously to the position indicated in the dotted lines, Fig. V, the glass of the major blank itself holding the segment against sliding and reinforcing to prevent any possible chipping.

Fig. VII illustrates the cutting of the completed lens from my improved blank, and it will be noted that the bottom line of the ordinary or usual shape of lens falls in such position as to cut off that portion of the

blank in which the apertures or sockets 5 have been formed so that no trace remains on the finished lens of the manner in which the segment was held and at the same time the segment has been satisfactorily held during the entire formation of the lens and all liability of slipping prevented.

From the foregoing description taken in connection with the accompanying drawings, the construction of my improved lens blank and the advantages possessed thereby, as well as the complete process of forming the lens, should be readily understood, and it will be seen that my improved lens blank embodies the pair of pieces of glass generally of different indices of refraction as has been commonly employed in the art, but which pieces of glass in place of being fused or permanently united one to the other, are detachably connected through the medium of a suitable cement, and are in addition mechanically locked against lateral movement, and that the blank thus put out may be ground and finished to the best advantage and may in fact be handled in any way in which it is possible to handle an ordinary fused lens blank without liability of relative displacement of the parts, while it will also be noted in conjunction with several forms of my invention illustrated that I laterally brace the projecting segment and thus eliminate the liability of chipping and the necessity of grinding down to quite thin form, and thus considerably reducing the size of the effective segment as sometimes occurs at present, even with the fused types of lens in which no lateral brace is provided for the projecting segment.

In connection with the necessity and utility of my present invention I would call particular attention to the fact that the best known cement which may be employed for the satisfactory uniting of the two parts of a lens, such as the bifocal illustrated, and which will have the proper retaining power, coefficient of expansion, transparency and the like, are cements or adhesives having a relatively low melting point, this melting point ordinarily being a great deal lower than the melting or softening point of the pitch or material commonly employed in securing the lens to the binding block. It is well known among lens grinders, however, that in the grinding and particularly in the polishing of an optical lens considerable care must be taken to keep the lens sufficiently lubricated so that the friction between the polishing or grinding tool and the lens will not heat the lens to a degree which will loosen it from the pitch, and if this care is not taken the lens will become so heated as to become loosened from the pitch and slip around on the block or fly off therefrom. Consequently it would be impossible on account of this heating effect to polish either

the plain or the bifocal side of my improved blank without very great probability that the parts would become so heated that the adhesive would be softened and serve as a lubricant, enhancing the sliding tendency of the segment rather than preventing it from sliding.

As before stated, it is, therefore, the primary purpose of my present invention to prevent this sliding or relative movement of the parts which is accomplished either by a mechanical lock or by the use of a supplemental cement or adhesive having a considerably higher softening point than that of either the cement which is intended to permanently unite the parts, or of the pitch or other substance used to retain the lens on the block. This cement may for example be a condensite or bakelite or similar product, serving to lock or retain the parts in desired relative relation one to the other, but being so disposed that this second locking medium will be cut away or removed and will not be present in the finished lens.

It will be understood that if desired, however, to permanently reinforce the lens, the plugs or other locking members, such as sticks for example, may be so disposed as to remain on the lens, but preferably adjacent the edge thereof, as indicated in Fig. VIII, to permanently assist in holding the parts, this, however, being a mere detail in the final cutting of the finished lens.

I claim:

1. An optical lens blank, including a major portion having a countersink, a segment having a portion fitting within the countersink, and a portion extending thereabove, and means for laterally bracing the projecting portion of the segment.

2. A blank for a two-part bifocal lens, comprising a major portion, a segment removably secured thereto, mechanical means for locking the parts against relative movement, and means laterally engaging the edge of the segment for preventing chipping thereof during the grinding operation.

Copies of this patent may be obtained for five cents each, by addressing the "Commissioner of Patents, Washington, D. C."

3. An optical lens blank, comprising a major portion and a supplemental portion, a cementitious medium interposed between and uniting the parts, and a second cementitious medium having a higher melting point than the first engaging both of the parts for locking the same against accidental relative movement.

4. A blank for a two part bifocal lens, comprising a major portion and a segment, a transparent cementitious medium interposed between and uniting the parts, and a second cementitious medium of considerably higher melting point than the first engaging and additionally uniting the parts.

5. A blank for a two part bifocal lens, comprising a major portion and a segment, a transparent cementitious medium interposed between and uniting the parts, a second cementitious medium of considerably higher melting point than the first engaging and additionally uniting the parts, said second cementitious medium being disposed on the blank to lie outside the normal field of vision as respects the finished lens cut from the blank.

6. The combination with a lens blank including a major portion and a segment attached thereto and a portion of the segment projecting beyond the surface of the major portion, of means surrounding the projecting portion of the segment for laterally bracing the same during the grinding operation.

7. A lens blank comprising a major portion and a segment, means for interlocking the segment with the major portion of the blank, and means surrounding the segment for laterally bracing the same against movement with respect to the major blank during the grinding operation.

In testimony whereof I affix my signature in the presence of two witnesses.

HARRY H. STYLL.
